TELESCOPING SOCKET FOR FLUORESCENT
LIGHT TUBESGeorge B. Kurtzon, Chicago, Ill., assignor to
Garden City Plating & Manufacturing Co., a
corporation of Illinois

Application January 3, 1947, Serial No. 719,972

1 Claim. (Cl. 173—328)

1

This invention relates to an electric light fixture, and particularly to a fixture adapted to hold a fluorescent light tube.

The present invention is concerned with means, including sockets, for mounting a comparatively thin elongated fluorescent light tube in a narrow, channel-shaped reflector. The sockets for holding the opposite ends of the fluorescent tube are easy to assemble with the reflector, and may be readily secured thereto in any desired position to accommodate a fluorescent tube of any length. One of the sockets is provided with a retractable section to permit the ends of the fluorescent tube to be positioned in the sockets, or removed therefrom, without the necessity of disturbing the set position of either socket and without having to turn the tube to any specific position. The sockets hold the opposite ends of the tube securely in position with snugly fitting resilient contacts.

The structure by which the various results are attained will be described in connection with the accompanying drawings, in which:

Figure 1 is a side elevation of a fixture embodying a reflector and two sockets assembled therewith in accordance with the present invention;

Fig. 2 is a bottom elevation of the fixture illustrated in Fig. 1;

Fig. 3 is a perspective view showing the two sockets with some parts disassembled to facilitate illustration of the structure;

Fig. 4 is a fragmentary detail perspective showing one of the sockets assembled with the reflector;

Fig. 5 is an end elevation of the other socket assembled with the reflector;

Fig. 6 is a longitudinal sectional view through the socket having a retractable section, taken substantially along the line 6—6 of Fig. 3;

Fig. 7 is a longitudinal sectional view through the fixed socket;

Fig. 8 is another longitudinal sectional view through the fixed socket taken at right angles to the view in Fig. 7;

Fig. 9 is a cross sectional view taken on the line 9—9 of Fig. 7; and

Fig. 10 is an end elevation of the fixed socket looking from the left side of Fig. 7.

In the drawings the reference numeral 2 indicates a channel-shaped reflector having lateral flanges 3 and 4 extending the entire length of each longitudinal edge of the channel. Both ends of the reflector are open so that sockets 5 and 6 may be slid into the reflector from either end. The sockets are preferably molded of hard rubber or any suitable plastic material.

2

Socket 5 comprises a tubular section 7 having an integral cross wall 8 spaced from its left end (as viewed in Fig. 6) to leave a substantially cylindrical space 9 defined by the cross wall and a circular flange 10 which is integral with section 7 and projects beyond the cross wall. A tubular metal member 11 extends entirely through cross wall 8 and is permanently secured thereto. The inner wall surface of the member 11 is threaded to receive a terminal screw 12. The contact area of member 11 is increased by means of a metal flange 13 which fits into a recess 14 and is substantially flush with the surface of cross wall 8. Flange 13 may be integral with member 11 or may be secured thereto in any suitable manner. A metal washer 15 encircles the end of member 11 on the opposite surface of cross wall 8 and is secured thereto by peening over the end of member 11, as indicated at 16, Fig. 6.

20 A coiled spiral metal spring 17 has its smaller end encircling the portion of member 11 adjacent flange 13 and is held in contact therewith by the retractable section 18 of the socket. The retractable section has an end wall 19. A metal washer 20 is positioned adjacent end wall 19 and spring 17 exerts pressure against the washer in order to provide an electrical contact at this end of the socket. Washer 20 may be secured to end wall 19 in any suitable manner, but it is preferably loose because the pressure of spring 17 is sufficient to hold it in place. End wall 19 has a comparatively large aperture 21 so that the terminal of a fluorescent light tube may project therethrough to engage an aperture 22 in metal washer 20. Aperture 22 is concentric with aperture 21 but is of smaller diameter and, with the aid of spring pressure from the coiled spring 17, will hold the terminal of the fluorescent light tube against rattling or accidental displacement. Section 18 of the socket is preferably provided with a semi-circular flange 18', projecting to the right (as seen in Fig. 6) and adapted to engage a portion of the end of the fluorescent light tube to facilitate positioning of the tube with its terminal engaging aperture 22.

40 The retractable section 18 of socket 5 is also tubular, and its outside diameter is slightly less than the inside diameter of section 7 so that it may slide freely therein. Sections 7 and 18 are maintained against separation by a metal plate 23 secured to a rib 24 by means of a plurality of screws 25. Rib 24 is integral with section 18 and extends longitudinally thereof. The other end of plate 23 slides in a groove 26 cut in the top of a rib 27 which is integral with section

7 and longitudinally aligned with rib 24. Metal plate 23 is provided with an elongated slot 28 in the part that slides in groove 26. A screw 29 projecting through slot 28 and into rib 27 limits the relative longitudinal movement between the retractable section 18 and section 7 and prevents the separation of the two sections. In order to prevent any tendency of sections 7 and 18 to rotate relative to each other, section 7 is provided on its inside surface with an integral rib 30 extending longitudinally thereof, and section 18 is recessed, as indicated at 31, to engage the sides of rib 30 at all times. Rib 30 and recess 31 are preferably diametrically opposite ribs 27 and 24. It will be obvious that the positions of rib 30 and recess 31 could be reversed.

A finger piece 32 is secured to metal plate 23 in any conventional manner to facilitate actuation of the longitudinal sliding movement of section 18 relative to section 7. In this connection it will be noted that the fluorescent tube itself could be used to push socket section 18 back into section 7 against the action of the coiled spring 17 but it is preferred to provide a finger piece because of the additional time saved by its use and the lesser possibility of damage to the fluorescent tube.

The circular flange 10 projecting to the left (Fig. 6) of member 11 is provided with recesses 33 for the passage of conventional wiring that is connected to metal member 11 by means of terminal screw 12. It is understood that the wiring of the fixture is entirely conventional and therefore will not be described in detail. The space 9 is closed by an insulation disk 34, which is preferably made of fiber board, although it may be made of paper or any similar material. Disk 34 is secured adjacent its periphery to the end of flange 10 by means of a screw 35. The edge of disk 34 is recessed, at a point diametrically opposite screw 35, to fit around a projection 36, integral with flange 10, to prevent rotation of the disk around the screw.

A support bracket 37 is secured to socket section 7 by means of an arm 38 which is secured by screws 39 to a rib 40 integral with socket section 7. Rib 40 is preferably positioned between the recesses 33. The support bracket has a bottom wall 41 and two parallel upstanding side walls 42 and 43. Arm 38 could be integral with wall 42 and bent at right angles thereto to overlie rib 40, but preferably it is formed as a separate piece and has a depending portion 44 which is welded to side wall 42, as indicated at 45. Insulating disk 34 is positioned between the end of flange 10 and side wall 42. Wall 42 is cut away, as indicated at 46 and 47, Fig. 5, adjacent each recess 33 so that the wires connected to terminal 12 will not project above the socket in an unsightly manner. Wall 43 is provided with an aperture 48 through which the wires may pass when they are to be connected to a source of electrical energy, or to an adjacent socket in which another fluorescent light tube is secured when a series of tubes is mounted in end to end relationship.

The bottom wall 41 has its ends turned downwardly, as indicated at 49 and 50, to engage flanges 3 and 4 of the reflector so that socket 5 may be slid longitudinally relative to the reflector. When the socket is properly positioned it is clamped against further longitudinal movement of the clamping plate 51. Clamping plate 51 is substantially co-extensive in area with bot-

tom wall 41 of the support bracket and has its ends 52 and 53 curved downwardly to fit beneath flanges 3 and 4 when the clamping plate is secured to wall 41.

- 5 Clamping plate 51 and bottom wall 41 are each provided with a pair of threaded apertures adapted to register with each other and are secured together by the screws 54. When screws 54 are loose socket 5 may be freely slid longitudinally of the reflector, but when the screws are tightened the socket is fixed in position. Socket 6 is secured to reflector 2 in the same manner as described in connection with socket 5. The support bracket 37', by which socket 6 is secured to reflector 2, is a duplicate of bracket 37 except that end wall 43' is shown as being imperforate. If desired, end wall 43' may also be provided with an aperture 48 or end wall 43 may be imperforate.
- 10 20 Socket 6 comprises a single tubular section having a circular flange 55 projecting beyond a cross wall 56. The space defined by the cross wall 56 and the end of circular flange 55 is closed by an insulating disk 58, similar to disk 34 and secured to the socket in the same manner. The space 57 is bisected by a rib 59 integral with cross wall 56. Rib 59 is flared outwardly to provide a wider portion, indicated at 60, Fig. 9, for increased strength.
- 25 30 35 40 45 50 Two metal members 61 extend through end wall 56 on opposite sides of rib 59. Each member 61 is provided with a threaded recess 62 to receive a terminal screw 63. A metal washer 64 is positioned around the end of each member 61 to increase the area of contact between the end of member 61 and the head of the screw. Washers 64 are held in place by peening over the ends of member 61, as indicated at 65, Fig. 8. The inner end of each member 61 has a resilient metal contact strip 66 secured thereto in any suitable manner. Metal strips 66 are bent outwardly so that a portion of each strip fits against the inside surface of socket 6, and then inwardly so that the ends of the strips are brought close enough to each other to cause them to resiliently engage the end of a fluorescent tube terminal which may be inserted therebetween. The extreme ends of strips 66 are bent back slightly, as indicated at 67, so that the fluorescent tube terminal cannot engage the extreme end of either strip.

55 60 65 A fiber disk 68 is positioned adjacent a shoulder 69 formed on the inside of the socket immediately in front of ends 67 of strips 66. Disk 68 is secured to shoulder 69 by means of a plurality of screws 70. In order to provide clearance for the heads of the screws the inside of the tubular wall of socket 6 may be grooved, as indicated at 71. Disk 68 has an aperture 72 which is small enough to leave an annular ring wide enough to conceal ends 67 of strips 66, and large enough to permit the insertion of a fluorescent light tube terminal so that the tube terminal may engage both of the strips 66 and be held resiliently therebetween.

70 75 The assembly and operation of the device is simple. Two sockets, one of which is a fixed socket and the other of which has a retractable section, each having a clamping plate loosely secured thereto, are slid along the channel reflector until they are properly positioned in accordance with the length of the fluorescent light tube to be used. The clamping plates are then tightened to hold the sockets in position. A fluorescent light tube is positioned between the

sockets by inserting one tube terminal in engagement with resilient contact strips in the fixed socket. The other end of the fluorescent tube is placed near the other socket and the retractable section is moved out of the way by means of a finger piece attached thereto. The unsecured end of the fluorescent tube is then manually aligned axially with both sockets and the finger piece is released. The pressure of a coiled spring moves the retractable section of the second socket towards the fixed socket until the tube terminal is resiliently engaged by a contact member in the second socket. The contact member has an aperture so that the tube terminal is engaged by the diameter of the contact member surrounding the aperture instead of merely by a single point. In order to remove the fluorescent tube the retractable section of the second socket is moved out of contact with the tube terminal and the tube is moved angularly a small distance. The tube may then be moved longitudinally to remove its other terminal out of contact with the fixed socket.

Although I have described one preferred embodiment of my invention in considerable detail, it will be understood that many details of structure may be modified or changed without departing from the spirit or scope of the invention. Accordingly, I do not desire to be restricted to the exact construction described, except as limited by the appended claim.

I claim:

A socket comprising a relatively fixed section and a section slidable therein, a plate connected at one end to said slidable section, an elongated slot in said plate adjacent its opposite end, a

5 screw extending through said slot into said fixed section to limit the sliding movement of said slidable section, a finger piece secured to said slidable section to move it inwardly relative to said fixed section, a projection extending longitudinally of, and integral with said fixed section, said slidable section having a recess engaging said projection to maintain said sections in axial alignment at all times, and a spring operable to move said slidable section outwardly to the limit of its travel automatically upon release of pressure applied against said finger piece.

10 15 GEORGE B. KURTZON.
